RAG RUG MAKING DEVICE

Joseph Woroneski, Croydon, Pa.

Application July 13, 1950, Serial No. 173,512

3 Claims. (Cl. 66—4)

1

This invention relates to a rag rug making device, and has for one of its objects the production of a simple and efficient frame having specially constructed staples for holding strips of rag material in place during the process of making a rag rug.

A further object of this invention is the production of a simple and efficient device or frame upon which a rag rug may be made without the use of warps.

Other objects of the present invention will appear throughout the following specification and claims.

In the drawing:

Figure 1 is a fragmentary perspective view of the rug making frame;

Figure 2 is a top plan view of a portion of the frame illustrating the manner in which the strips of material are placed upon the frame while beginning to knit the rug;

Figure 3 is a front elevational view of a portion of the frame illustrating the relative positions of the anchoring pins and staples;

Figure 4 is a fragmentary top plan view of the frame and illustrating the type of knitting produced thereon;

Figure 5 is an end elevational view of the frame illustrating one position of the strip of material engaging the two front notches or recesses in the end staple;

Figure 6 is an end elevational view of the frame illustrating the position of the strip of material as it is moved to a position to engage the rear notch of the end staple;

Figure 7 is an end elevational view of the frame illustrating a further position of the strip of material while knitting; and

Figure 8 is an enlarged side elevational view of one of the staples.

By referring to the drawing in detail, it will be noted that 10 designates the base of the frame, which may consist of a flat rectangular piece of wood or other material of a desired length. A plurality of upstanding members or staples 11 are driven into the upper face of the base 10 in spaced parallel relation to hold the staples 11 in upright positions, as shown in Figures 1 and 3. Each staple 11 is provided with a pair of forward notches 12 and 13, or recesses which are bent into the forward leg 14 of the staple. These notches 12 and 13 are arranged one above the other, as shown. Each upstanding member or staple 11 also is provided with a rear leg 15 having one notch or bent recess 16. The upper end of each staple inclines rearwardly, as shown in Figures 5, 6 and 7.

2

A plurality of upstanding anchoring pins 17 are driven into the upper face of the base 10 rearwardly of the line of staples 11 and in spaced staggered relation to the staples 11 as shown in Figures 2 and 3. The pins 17 have their upper ends rearwardly inclined to prevent the strips of material from becoming accidentally detached.

From the above description, it will be noted that present device embodies a base having a desired number of staple-shaped wires 11, equally spaced and driven into the support 10. These staple-shaped wires 11 have two notches in the front legs and one notch in the rear legs thereof. These notches are for the purpose of holding the strips of rag material in place during the process of making a rug. Figure 2 illustrates how the rug is begun and the method of knitting is as follows:

After cutting some material, old garments, and the like, into strips of about one-half inch or wider, the strips are sewed together to provide one continuous strip. The width of rug desired is measured to determine the number of staples 11 which are to be utilized in knitting. A loop 18 is formed in the strip 19, and preferably is sewed to fit around the anchoring pin 17 at one end of the base 10. The strip 19 is then drawn forwardly at an incline to pass across the bottom notch 12 of the first staple 11, then around the second pin 17 and back and forth from staple to pin. The remaining portion of the strip 19 is then passed from the last utilized pin 17 to engage the top notch 13 of the last utilized staple 11. A conventional hook 20 is used to lift the bottom strip indicated as A in Figure 5, up over and across the top strip indicated as B in Figure 5, and over the top of the upstanding member or staple 11, to a position in back of the member 11 where it engages notch 16. Then the strip B is moved down from the top notch 13 to the lower notch 12 at which time the strip B is in a position ready for the next round. This procedure is repeated at each member 11 or staple, back and forth until the desired length of rug is completed.

The pins 17 and 17^a are necessary to begin the rug. As the rug is being made, the pins are used to pin or stretch the rug away from the staples, after one transverse row of loops are formed in the manner indicated generally in Figure 4.

It will be noted that the notch 13 is inset relative to the notch 12 and the leg 14. The legs are spaced apart at least one inch, or more, to keep the loops large enough and to permit the making of a rug from rag strips. The knitting is continuous, and when one end of a row is

completed, the method of forming the second row is the same only in a reverse direction.

It should be noted that the invention consists mainly in the knitting frame and the arrangement of the spaced aligned staples having the specially arranged notches formed in the legs of the staples, in conjunction with the anchoring pins which are carried by the base 10 in staggered relation upon the base 10. It is realized that the method of knitting may be changed or modified or devised by the user of the frame without departing from the spirit of the invention, but it should be noted that the frame herein described provides a frame wherein a single continuous length or strip of material may be used to knit a rug without the necessity of providing warps or warp strips.

Certain detail changes in mechanical structure in the frame may also be made without departing from the spirit of the invention, so long as these changes fall within the scope of the appended claims.

Having described the invention, what I claim as new is:

1. A rag rug knitting frame comprising a base, plurality of transversely extending upstanding members secured to the base in spaced relation to define a row of members extending longitudinally of the base, each member having a front portion having a plurality of vertically spaced notches, each member also having a rear portion having a single notch rearwardly of the notches in the front portion thereof, anchoring pins carried by the base rearwardly of the members and in staggered relation thereto, the notches and pins being adapted to receive a continuous knitting strip in a manner to facilitate the knitting of a rug with a single continuous knitting strip by anchoring the strip to one pin, then passing the strip around the bottom front notch of the adjacent member, then around the second pin and then progressively around the bottom notch of the next member and next pin, then returning the strip to engage the top front notch of the last member and finally lifting the portion of the strip which engages the lower front notch over the top of the last member to engage the rear notch, and then continuing with the strip in like manner with respect to each member until the row of

knitting is completed, the pins also providing anchoring means for the strip as the strip is being stretched away from the members to knit succeeding rows.

5 2. A rag rug knitting frame comprising a base, a plurality of transversely extending upstanding members secured to the base in spaced relation to define a row of members extending longitudinally of the base, each member having a front portion having a plurality of vertically spaced notches, each member also having a rear portion having a single notch rearwardly of the notches in the front portion thereof, anchoring pins carried by the base rearwardly of the members and in staggered relation thereto, the notches and pins being adapted to receive a continuous knitting strip to facilitate the knitting of a rug with a single continuous knitting strip.

20 3. A rag rug knitting frame comprising a base, a plurality of transversely extending upstanding members secured to the base in spaced relation to define a row of members extending longitudinally of the base, each member having a front portion having a plurality of vertically spaced notches, each member also having a rear portion having a single notch rearwardly of the notches in the front portion thereof, anchoring pins carried by the base rearwardly of the members and in staggered relation thereto, the notches and pins being adapted to receive a continuous knitting strip to facilitate the knitting of a rug with a single continuous knitting strip, said pins being inclined rearwardly and upwardly relative to said members.

35 JOSEPH WORONESKI.
